MAGAZINE LEAD PENCIL

Alfred Woelz, Berlin, Germany, assignor, by
mesne assignments, to Pencil Mechanism Cor-
poration, a corporation of New York

Original application September 16, 1922, Serial
No. 588,688, and in Germany July 21, and
August 5, 1922. Divided and this application
March 31, 1927. Serial No. 180,000.

13 Claims. (Cl. 120—17)

This invention relates to a magazine lead pencil which is adapted to contain a large number of strips of lead which are successively brought into operative position by means of a device which allows the lead strip in use for the time being to be fed forward by a definite length; this present application being a division of my co-pending application Serial No. 588,688, filed September 16, 1922.

10 My improved magazine lead pencil is illustrated in the accompanying drawing, in which:

Fig. 1 is a side view of my improved pencil;

Fig. 2 is a view of the lower portion of my pencil, at right angles to Fig. 1;

15 Fig. 3 is a longitudinal section through my pencil on an enlarged scale;

Fig. 4 is an elevation of the feeding mechanism with the operative parts in a different position;

20 Fig. 5 is a detail showing a manner of joining the two parts of the holder;

Fig. 6 is a longitudinal section, parts broken away, through a modified form of my invention;

25 Fig. 7 is an elevation of the modified feeding mechanism, at right angles to the section shown in Fig. 6.

The same reference characters refer to the same parts throughout the several views.

As in the original application, supra, my improved pencil comprises a tubular holder terminating at one end in a conical mouth piece 2 and closed at the other end by a cover or cap 3. The strips of lead are contained in a compartment 4 of the holder and form a bundle. The bottom of this compartment is formed by a dish 5 fixed upon 30 the upper end of a central tube 6 serving as a guide for the individual strips of lead. The bottom 5 of the compartment 4 slopes towards a central outlet 7, so that the strips of lead have a tendency to crowd towards the center and the strip situated in the middle of the bundle enters into the outlet 7.

At its lower end the central guide tube 6 is provided with screw-thread 8 by means of which it is screwed into the tapped upper portion of a sleeve 9, which is of conical shape and fits into the conical mouth piece 2 of the holder or handle 1. The sleeve 9 is secured within the mouth piece 2 of the holder by means of a separate mouth piece 10, which is screwed by a male screw-thread 50 at its upper end into the female screw-thread 11 in the lower portion of the sleeve 9 and abuts with a shoulder against the mouth piece 2 of the holder forming a continuation of the same. The guide-tube 6 is at its lower end provided with jaws 12' and 12'', Fig. 3, which close upon the

strip of lead contained in the guide tube and hold it resiliently in position.

Upon the central guide-tube 6 is slidably mounted a sleeve 14, in which is fulcrumed at 16, by means of a clip or strap 15, a double armed lever (or levers—see Fig. 6) 17—18. The lower arm 17 of this lever is at its inner face provided with teeth 17—T, while the other arm 18 fulcrumed at 16 contacts with the inclined or cone shaped bottom of the collar 23. Slidable upon the sleeve 14 is mounted a collar 23. A spring 26 normally forces said collar downward, and a suitable pin or ridge 31 limits the upward movement of the collar 23 upon the sleeve 14.

Suitable slots are provided in both the sleeve 14 and central guide-tube 6, to permit the passage of the toothed end of the lever-arm 17, so that the spring 26, forcing downward the collar 23, may force the upper end of the lever arm 18 outward, and the lower arm 17, on which are the teeth 17—T, toward and into gripping contact with the lead strip. A spring 32 normally tending to retract the lever arm 17 is in this case attached to the arm itself.

I may use a single double arm lever and a lead 80 abutting strip 21 carried in the sleeve 14, as illustrated in Figs. 3 and 4, but I now prefer to make use of a pair of such arms, disposed on opposite sides of the lead, as illustrated in Fig. 6.

In order to insure proper sequence in the movement of the parts of the feeding mechanism, I have provided a spring 36, fastened to a non-moving part 9 of the mechanism, and having the free end 38 thereof in contact with a projection (or a depression) 37 formed on (or in) the sleeve 14. The function of the spring 36 being to offer resistance to the longitudinal movement of the sleeve 14, so that friction between the sleeve 14, double-armed levers 17—18 and the collar 23 may not commence the longitudinal movement of the sleeve 14 upon the central guide tube 6 before the springs 32 have operated to withdraw the toothed end of the lever 17 from contact with the lead strip, when the trigger 30 is forced upward; or before the wedging action of the cone 24 has overcome the tension of the springs 32 and forced the toothed ends of the levers 17 into contact with the lead strips when the spring 26 reverses the motion of the collar and forces it downward. The use of the tension spring 36 insures a lead feed equal to the longitudinal movement of the sleeve 14 upon the tube 6.

The operation of the mechanism which effects 110

the advance of the lead takes place as follows; reference being had to Fig. 3 of the drawing:

The writing position of the parts are illustrated in Fig. 3 (also in Fig. 6), and the advancement of the lead is accomplished by simply forcing upward the trigger 30, which causes a like movement of the collar 23 of which it forms a part, and compresses the spring 26. As the collar 23 commences its upward movement, the cone 10 surface is withdrawn from under the inclined end of the arm (or arms) 18, and the spring 32 retracts the toothed end of the lever 17 until it is out of contact with the lead. The collar 23 then reaches the upward limit of the movement 15 longitudinal on the sleeve 14, and contacting with the limiting device 31, its further upward movement carries with it the sleeve 14 and the double-armed levers pivoted thereto, until it reaches the limit of its upward travel. The trigger 20 being then released the spring 26 reverses the movement of the collar 23, and due to the resistance of the spring 36 the first movement of the collar 23 downward will not move the sleeve, but will cause the levers 17 to again grip the lead, 25 and its continued downward movement thereafter will carry forward the lead as far as the limits of the mechanism will permit.

Having described my invention, what I claim as new and desire to secure by Letters Patent is:

30 1. In a lead pencil, the combination of a tubular holder adapted to contain strips of lead, a cap at one end of said holder and a conical mouth piece at the other, a further cylindrical magazine for strips of lead disposed within said holder, 35 a bottom in said magazine and said tubular holder which slope towards a central opening, a guide-tube for leading said lead strips from the lower of said central openings to said mouth piece, a slidable sleeve upon said guide-tube, a 40 double-armed lever fulcrumed upon said sleeve, one arm of which is adapted to engage the lead in said guide-tube, a spring tending to raise said arm off said lead, a slidable bevelled collar upon 45 said sleeve adapted to cooperate with the bevelled end of the other arm of said lever, a spring disposed between said collar and the bottom of said holder and tending to keep said collar and the bevelled face on the lever arm in engagement and the other arm of the lever down 50 upon the lead in said guide-tube, a trigger upon 55 said collar adapted to project through a slot in said holder and a pin upon said sleeve adapted to be engaged by said collar and to be carried along by it when said trigger is pulled away from said mouth piece.

2. In a lead pencil, the combination of a tubular holder consisting of two fitted-together parts, one part adapted to contain a store of strips of lead and the other the feeding device for said 60 strips, a cap at one end of said holder and a conical mouth piece at the other, a further cylindrical magazine for strips of lead disposed within the magazine portion of said holder, bottoms in said magazines which slope towards central openings, a guide tube for leading said lead strips from the lower of said central openings to said mouth piece, a slidable sleeve upon said guide-tube, a double-armed lever fulcrumed upon said sleeve, one arm of which is adapted to engage the 65 lead in said guide-tube, a spring tending to raise said arm off said lead, a slidable bevelled collar upon said sleeve adapted to engage with the bevelled end of the other arm of said lever, a 70 spring disposed between said collar and the bottom of said holder and tending to force said

bevelled collar against the bevelled arm of said lever and the other arm of said lever in engagement with the lead in said guide-tube, a trigger upon said collar adapted to project through a slot in said holder and a pin upon said sleeve adapted to be engaged by said collar and to be carried along by it when said trigger is pulled away from said mouth piece.

3. In a lead pencil, the combination of a tubular holder adapted to contain strips of lead, a cap at one end of said holder and a conical mouth piece at the other, a bottom in said tubular holder which slopes toward a central opening, a guide-tube leading from said opening to said mouth piece, a sleeve slidable upon said guide-tube, a double-armed lever fulcrumed in said sleeve, a collar mounted on said sleeve so as to have a limited longitudinal movement thereon, superimposed slotted openings in said guide-tube and said sleeve adapted to pass the lower arm of said lever, a spring normally tending to withdraw said arm from said openings and a spring normally tending to force said collar between the upper arm of said lever and said sleeve so as to force the lower arm of said lever through said 100 slotted openings.

4. In a lead pencil, the combination of a tubular holder adapted to contain strips of lead, a cap at one end of said holder and a conical mouth piece at the other, a bottom in said tubular holder which slopes toward a central opening, a guide-tube leading from said opening to said mouth piece, a sleeve slidble upon said guide-tube, a double-armed lever fulcrumed in said sleeve, a collar mounted on said sleeve so as to have a limited longitudinal movement thereon, superimposed slotted openings in said guide-tube and said sleeve adapted to pass the lower arm of said lever, a spring normally tending to withdraw said arm from said openings; a spring normally tending to force said collar between the upper arm of said lever and the said sleeve so as to force the lower arm of said lever through slotted openings; and means for retarding the free movement of said sleeve upon said guide-tube in either direc- 120

5. In a lead pencil comprising means providing a magazine, a tip, and means to guide strips of lead from said magazine to said tip, the combination of mechanism to cause strips of lead to be advanced to said tip by a step-by-step movement; said mechanism including gripping means comprising one or more jaws each provided with a lead gripping surface and arranged for movement toward and away from said tip and for movement of said lead gripping surface out of and into contact with the lead, means comprising a spring to cause said gripping means to grip the lead during certain portions of the operation thereof, and means comprising another spring 135 to cause the gripping means to release the lead during other portions of the operation thereof; and manually operable means to cause the operation of said mechanism.

6. In a step-by-step lead pencil, a plurality of longitudinally movable lead grippers, resilient means tending to spread said grippers, a longitudinally movable gripper-operating member arranged to normally maintain said grippers in engagement with a lead in the pencil and when reciprocated to impart movement to said grippers and to press said grippers against a lead during the major part of their downward movement, and resilient means adapted normally to 150

- press said longitudinally movable member against said grippers.
7. In a step-by-step lead pencil, a longitudinally movable member, a plurality of longitudinally movable lead-gripping jaws, a spring-pressed member acting normally to cause said lead-gripping jaws to grip a lead therebetween for writing purposes, and means to reciprocate said jaws in response to the movement of said longitudinally movable member.
8. In a step-by-step lead pencil, the combination of a longitudinally movable gripper-supporting element, a plurality of grippers rockingly supported on said element, operating means to reciprocate said grippers and to cause the grippers to grip and release a lead in the pencil at different points in their cycle of movement to propel the lead step-by-step through the pencil, and exteriorly accessible means to actuate said operating means.
9. In a magazine pencil including a casing, a plurality of rockingly-mounted lead-gripping and propelling elements formed with cooperating jaw portions each movable inwardly against a lead in the pencil, and operating mechanism for said leading-propelling elements.
10. In a step-by-step pencil including a casing, a longitudinally-movable lead-gripping unit including a plurality of outwardly spring-pressed jaws, a longitudinally-movable spring-pressed operating member tending to thrust said jaws toward each other and against a lead in the pencil in opposition to their springs, and exteriorly accessible means for moving said operating member in opposition to its spring.
11. In a step-by-step pencil including a casing, a plurality of longitudinally-movable grippers outwardly spring pressed, a longitudinally-movable gripper-operating member, resilient means tending to press said operating member against said grippers to hold them in closed position, ex-
- teriorly accessible longitudinally-movable means for actuating the gripper-operating member, means to limit the forward movement of the grippers, and means to limit the rearward movement of the grippers before the end of the rearward movement of the gripper-operating member.
12. In a step-by-step pencil, a slotted lead guide tube, a plurality of outwardly spring-pressed grippers formed with cooperating jaw portions adapted to extend within the slots in the guide tube to grip a lead therein, said grippers and said tube being mounted for relative longitudinal movement, a gripper-operating member longitudinally slidably mounted with respect to said guide tube and said grippers, a spring normally acting longitudinally of the pencil to hold said gripper-operating member in jaw-closing position, and actuating means for causing relative longitudinal movement of the parts and for compressing said spring to permit the release of said jaws.
13. In a step-by-step pencil, a slotted lead guide tube having a lead-holding portion at its lower end, a plurality of outwardly spring-pressed grippers formed with cooperating jaw portions adapted to extend within the slots in the guide tube to grip a lead therein, said grippers and said guide tube being mounted for relative longitudinal movement, a gripper-operating member longitudinally slidably mounted with respect to said guide tube and said grippers, a spring normally acting to press said operating member downwardly to hold said gripper-operating member in jaw-closing position, and actuating means for causing relative longitudinal movement of the parts and for compressing said spring to permit the release of said jaws.
